UNITED STATES PATENT OFFICE

2,533,329

ASH DISPOSAL SCREW

William M. Schweickart, Bay Village, and Fred G. Julyan, Euclid, Ohio, assignors, by mesne assignments, to Iron Fireman Manufacturing Company, Portland, Oreg., a corporation of Oregon

Application October 2, 1944, Serial No. 556,686

3 Claims. (Cl. 198—213)

1

This invention relates to improvements in automatic coal burners.

The object of the invention is to provide an economical and effective ash disposal receiving the ashes from the ash ring discharge and delivering them into adjacently placed ash barrels.

Other objects and advantages of the invention will appear from the following description considered in connection with the accompanying drawings in which

Fig. 1 is a perspective view of the stoker with the bin collector omitted;

Fig. 2 is a central section through the ash elevator in a plane parallel to the ash removal screw with the discharge head rotated to show the discharge spouts; and

Fig. 3 is a fragmentary section of the base of the ash elevator structure on line 3—3 of Fig. 2.

The specific embodiment shown in Fig. 1 comprises a drive unit B, a burner unit C and an ash discharge unit D.

A coal collector unit, not shown, is positioned in the coal bin and supplies coal to the coal feed tube 22 in which is positioned the coal screw 21, with the collector unit driven from the coal feed screw 21. A suitable collector unit is shown and described in our Patent No. 2,233,085.

Where the conveyor tube 22 requires a bend, this is preferably made as an angle, for instance, a right angle, through a feed knuckle (not shown) provided for conveying the coal around the angle.

The drive unit B includes the motor with its controls, the blower and air supply, the drive for the coal feed and ash discharge screws, the grate rotor drive and gas withdrawal construction.

The drive assembly is mounted on a base 72 provided with a longitudinal cylindrical passage for the coal to which sections of the coal feed tube 22 are connected and through which the last section of the coal feed screw 21 passes. The base 72 above the feed end of coal passage 73 carries a cradle supporting motor 75. The motor 75 is bolted to the reduction gear casing 86, which in turn is supported from a bracket of the base 72. The rear end of motor shaft carries the rotor of blower 78. A suitable muffler is preferably provided comprising a housing surrounding the blower air inlet and extending to the right in the form of a rectangular closed compartment projecting beyond blower casing sufficiently to accommodate the larger air inlet tube 82. The air inlet tube 82 provides a definite column of air whose vibration period may be varied by altering the length of tube 82 until the inlet air noise is reduced to a minimum.

2

The various conveying mechanisms are driven by motor 75 through a drive shaft suitably connected to the coal feed screw 21, and to the ash removal apparatus.

5 This apparatus includes an ash removal shaft 89 journaled in the base 72 and the coal feed screw 21 and the ash removal shaft 89 both extend to the burner unit C. In the form illustrated herein, the ash removal shaft 89 is provided with a sprocket connected by a chain with another sprocket on a drive shaft from the motor. A handle 100 at the left of the unit is mounted on a clutch release arm to control the connection to the drive shaft.

10 15 The burner unit C includes a rotating grate structure 189 which surrounds an inner retort of the burner unit C of the type in which the coal is forced upwardly through the bottom of the burner retort or pot structure, burning in the upper portion thereof and traveling over the edge onto the grate structure through which the ashes pass.

An ash trough 209 extends around and below the ash table segments for the direct discharge of ashes from the ash table. The ashes carried around the ash table are continuously discharged by a simple scraper arrangement and a suitable arrangement is provided for automatically removing the ashes from the burner unit C and discharging them at an appropriate point, the construction preferably including an ash removal conveyor and an elevator for transferring the ashes from the conveyor to a suitable discharge point. In the form illustrated the ashes are removed from the ash discharge chamber by ash removal tube 285 mounted in the burner body. Tube 285 extends to an appropriate point and is shown as terminating adjacent drive unit B (Fig. 1). At this point a suitable elevator unit D is positioned to receive the ashes. A convenient construction is disclosed, employing an arrangement in which the ash removal tube 285 terminates in an elevator pocket 287 (Figs. 2 and 3) formed in elevator base 288. Ash removal screw 218 terminates at the pocket while the shaft 89 on which the screw is mounted extends through the pocket and a suitable bearing 289 at the opposite side of the elevator base 288, and thence to the drive mechanism as already set forth.

40 45 50 55 An elevator tube 290 is mounted in elevator base 288 extending from pocket 287 upwardly in any desired direction to permit discharge at any appropriate point dictated by local conditions, the angle of tube 290 being readily adjusted by clamping base 288 in any desired rotated position about

ash removal tube 285 through clamping screw 291. An elevator screw 292 is positioned in tube 290 to pick up ashes discharged into pocket 287 and raise them in tube 290 to a discharge at the upper end of the tube. Various methods of mounting and driving screw 292 may be employed, and preferably are arranged to permit accessibility and removal of screw 292 without dismantling the supporting and driving arrangement. In the form illustrated, the screw 292 is driven from a bevel gear 293 on shaft 89 driving bevel gear 294 mounted on elevator base 288 and carrying sprocket 295 which through sprocket chain 296 drives sprocket 297 on elevator shaft 298 mounted in thrust bearing 299 in the elevator base 288.

Means may be provided for protecting the lower end of the shaft 298 from the ashes in pocket 287, as by protector sleeve 300 mounted in fixed position on base 288 surrounding elevator shaft 298, and serving as a guide and support for the tubular elevator screw 292 rotatable around sleeve 300. Screw 292 is suitably attached to shaft 298 above sleeve 300, as by pins 301 and spacer rings 302.

Sleeve 300 is maintained in proper spaced relation to shaft 298 and screw 292 by suitable bushings such as the leaded bronze bushings 292 between the upper end of sleeve 300 and shaft 298, and leaded bronze bushing 283 between the lower end of screw 292 and tube 300. A suitable sealing bearing is provided between the lower end of screw 292 and the base 288 and comprises a leaded bronze thrust washer 305 and a suitable resilient backing such as rubber rings 306 surrounding shaft 298.

To align the bearings at the ends of shaft 298, a suitable self-aligning joint is provided, such as that illustrated in Fig. 2, in which the lower section of shaft 298 is provided with a tongue 303 held in a corresponding slot 304 in the upper section by pin 305, the construction being arranged to permit the very slight play necessary to assure smooth running in the bearings. Screw 292 will of course be broken at the flexible connection as shown.

A suitable discharge arrangement is provided at the upper end of elevator tube 290. This may comprise a discharge head 306 mounted on the upper end of elevator tube 290 and carrying an upper bearing 307 for the elevator shaft 298. Head 306 is provided with suitable spout discharge means, the illustrated construction employing two discharge spouts 308 and 309, each of which may be provided with a flexible tube 310 clamped thereto for directing the ashes to any suitable receptacle, such as ash can 311 (Fig. 1). A suitable hinged door 312 may be provided opposite spouts 308 and 309 to permit access to the mechanism and to serve as an overflow outlet for ashes when the spouts 308 and 309 are filled or obstructed.

This application is a division of our application Serial No. 383,432 (now Patent No. 2,359,445), which is a division of our original application

Serial No. 161,494, filed August 28, 1937 (now Patent No. 2,306,189).

We claim:

1. In a stoker the combination with a motor drive, of a first worm feed comprising a conveyor tube containing a first worm driven from said motor drive and adapted to receive a supply of material at one end and deliver it at its other end, a second worm feed extending at an angle to said first worm feed and comprising a conveyor tube and a hollow worm therein having a material receiving end adjacent said delivery end of said first feed worm, a housing adjustable to various settings around the axis of said first conveyor tube and connected thereto, means on said housing supporting said second conveyor tube, a drive shaft in said hollow worm connected thereto and having a supporting bearing in said housing adjacent said receiving end of said second worm, and means for driving said drive shaft from said main worm comprising rotary means carried by said housing and connected to said drive shaft adjacent said supporting bearing in all adjusted positions of said housing.
- 5 10 15 20 25 30 35 40 45 50 55 60 65
2. A stoker feed apparatus as set forth in claim 1 in which the hollow worm and its drive shaft are in sections connected by a pivot joint between the separate sections of said shaft and worm.
